UNITED STATES PATENT OFFICE.

SAMUEL E. AREY, OF FELLOWS, CALIFORNIA.

SUCKER-ROD HANGER.

1,242,305.

Specification of Letters Patent.

Patented Oct. 9, 1917.

Application filed January 22, 1916. Serial No. 73,746.

To all whom it may concern:

Be it known that I, SAMUEL E. AREY, a citizen of the United States, residing at Fellows, in the county of Kern and State of California, have invented a new and useful Sucker-Rod Hanger, of which the following is a specification.

By way of explanation it may be stated that sucker rods of the sort commonly employed in connection with well operations ordinarily are removed in sections each of a considerable length. These sections of the sucker rods not infrequently are laid down horizontally on suitable brackets, the consequence being that the sections of the sucker rods sag between the brackets and become more or less bent and distorted to their obvious detriment. Further, such a disposition of the sucker rod sections places them in positions which are more or less inaccessible to a well operator, since the sucker rods must be turned up endwise into a vertical position, before they can be used again in connection with a well.

The present invention aims to provide novel means whereby the sections of a sucker rod may be hung up in vertical positions within easy reach of the operator, the construction being such that a relatively large number of sucker rods may be disposed in a small compass, adjacent the operator and so positioned that they may be connected and lowered into the well when occasion demands.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—

Figure 1 shows the invention in side elevation;

Fig. 2 is a top plan showing one of the sucker rod supports, the shaft of the support being shown in section;

Fig. 3 is a fragmental longitudinal sec-

tion showing a portion of one of the sucker rod supports;

Fig. 4 is a transverse section taken through the rim of one of the sucker rod supports.

Fig. 5 is a side elevation showing a modified form of the invention.

In carrying out the present invention there is provided a frame which may embody a member 1, the same being if desired, a portion of a derrick. Disposed transversely of the member 1 and secured thereto are attaching plates 2. Disposed approximately parallel with the member 1 and in a vertical position is an upright 3 engaged by U-bolts 4 passing through the attaching plates 2 and straddling the member 1. Spacers 5 may be interposed between the upright 3 and the attaching plates 2. Nuts 6 are threaded onto the arms of the U-bolts 4 and bear against the rear faces of the attaching plates 2.

Secured as shown at 7 to the upper end of the upright 3, and ordinarily disposed horizontally, is an arm 8 which may be connected to the upright 3, additionally, by means of an angle bracket 9. Extended between the outer end of the arm 8 and the upright 3 is an inclined brace 10 secured as shown at 11 to the arm 8 and to the upright 3 respectively.

Journaled for rotation in the outer end of the arm 8 is an upright shaft 12 to which is secured a ball race or head 14, the ball race being adjustably held to the shaft 12 by means of a set screw or the like indicated at 15 to the end that the shaft 12 may be raised and lowered for adjustment. The ball race 14 coacts with a ball race 16 mounted on the outer end of the arm 8 and preferably secured thereto. Antifriction balls 17 are interposed between the ball races 16 and 14, to the end that the shaft 12 may be rotated easily.

The invention comprises a support denoted by the numeral 18 and preferably of circular form, the support 18 being trough-shaped in cross section embodying a bottom 19, an inner flange 20 and an outer flange 21. Spokes 22 project inwardly from the inner flange 20 and are connected at their inner ends, to a hub 23 rotatable on the shaft 12. Upwardly inclined spokes 24 are connected at their outer ends with the inner flange 20 and at their inner ends are connected with a hub 25, disposed above the

- hub 23 and rotatable on the shaft 12. A collar 26 surrounds the shaft 12 below the lower edge of the hub 23 and is held in place adjustably by means of a securing element 27, the construction being such that the support 18 may be raised and lowered at will. Anti-friction balls 28 may be interposed between the collar 26 and the lower end of the hub 23.
- 10 In the outer flange 21 and in the bottom 19 of the support 18 inwardly extending notches or openings 29 are fashioned, the mouths of the notches or openings 29 being flared, as clearly shown at 30 in Fig. 2.
- 15 Disposed upon both sides of each of the notches 29 in the support 18 and carried at their ends by the flanges 20 and 21 are shafts 31. Cams 32 are mounted to swing vertically on the shafts 31, and are located between the flanges 20 and 21. The inner ends of the cams 32 lie adjacent the notches 29 and are provided with teeth 33. The lower inner edges of the cams 32 are beveled, as shown at 34, the inner corners of the cams 32 being beveled as shown at 35, adjacent the outer edge of the support 18. The cams 32 are fulcrumed intermediate their ends on the shafts 31, the adjacent ends of the cams 32 being provided with shoulders 36, engaged by the ends of a bowed spring 37, attached intermediate its ends by means of a securing element 38 to the bottom 19 of the support 18.
- Disposed below the support 18 are any 35 desired number of supports 39, but one support 39 being shown. The supports 39 are identical in construction with the support 18 saving for the fact that the supports 39 are of successively decreasing diameters.
- 40 In practical operation, a length of sucker rod is inserted into one of the notches 29 of the support 18 and is given a slight upward movement, the beveling of the cams 32 as shown at 34 and 35 facilitating the introduction of the sucker rod between the cams. When the sucker rod section is elevated in the manner hereinbefore described, the cams 32 tend to swing in the direction of the arrow A in Fig. 3, the springs 37 being put 50 under tension. So soon, however, as the upward movement of the sucker rod ceases, the teeth 33 on the cams bite into the sucker rod and prevent downward movement thereof, the springs 37 rendering the action of 55 the cams 32 more rapid and positive.
- Owing to the fact that the supports 18-39 are of circular outline and since these supports are mounted to rotate, the sucker rod sections may be inserted readily into the 60 supports. Further, owing to the fact that

the supports 18 and 39 are of circular outline, and because the support 39 is of less diameter than the support 19, a large number of sucker rods may be placed in a small compass, within easy reach of the operator. 65

In Fig. 5 of the drawings, a modified form of the invention is shown. In this form of the invention, the support 100 is straight instead of being of circular outline as hereinbefore described, the support being provided with cams 101 and being constructed substantially like the support hereinbefore alluded to, saving for the fact that the support 100 is straight. The support 100 may be provided adjacent its ends and in 70 its edge with notches 102 adapted to receive pins 103, carried by the lower ends of hangers 104 adapted as shown at 105 for suspension from an overhead frame of any desired sort. (Not shown).

Having thus described the invention, what is claimed is:—

1. In a device for holding sucker rods, a frame; a support assembled with the frame, the support being provided with openings in its outer side; sets of cams pivoted to the support on opposite sides of the openings; and a bowed spring secured to the support intermediate the cams of adjoining sets, the spring coacting with the cams of adjoining sets to cause the cams to coöperate with the sucker rods when placed in the openings. 85

2. In a device of the class described, an overhead frame; a depending vertical shaft having its upper end extended through the frame and journaled for rotation in the frame, the shaft being vertically adjustable in the frame; a head adjustable longitudinally on the upper end of the shaft and engaging the upper edge of the frame to 100 limit the downward movement of the shaft; means for holding the head on the shaft in adjusted positions longitudinally of the shaft to permit a raising and a lowering of the shaft; a pair of hubs adjustable longitudinally on the shaft and disposed below the frame; means for securing the hubs to the shaft in adjusted positions longitudinally of the shaft; and upper and lower holders supported for rotation on the respective hubs, the upper holder being of larger diameter than the lower holder. 105

In testimony that I claim the foregoing as my own, I have hereto affixed my signature in the presence of two witnesses.

SAMUEL E. AREY.
